CLAIM

I claim the ornamental design for an access gate with lights, as shown and described.

DESCRIPTION

FIG. 1 is an enlarged perspective view of the access gate with lights which are not lit.

FIG. 2 is a front elevational view of the access gate with lights shown in FIG. 1.

FIG. 3 is a rear elevational view of the access gate with lights shown in FIG. 1.

FIG. 4 is a top view of the access gate with lights shown in FIG. 1. The bottom view being the same as the top view.

FIG. 5 is an enlarged perspective view of the access gate with lights.

FIG. 6 is a front elevational view of the access gate with lights in a lit condition.

FIG. 7 is a rear elevational view of the access gate with lights in a lit condition; and,

FIG. 8 is a top view of the access gate with lights.

The bottom view being the same as the top view.

The access gate with lights may be of indeterminate length as indicated by the bisecting broken lines in all the FIGURES.

The broken lines in the drawings form no part of the design.
